UNITED STATES PATENT OFFICE.

WILLIAM BRYAN SHROPSHIRE, OF PITTSBURG, GEORGIA.

LEVELING-ROD.

SPECIFICATION forming part of Letters Patent No. 778,080, dated December 20, 1904.

Application filed June 18, 1904. Serial No. 213,116.

To all whom it may concern:

Be it known that I, WILLIAM BRYAN SHROPSHIRE, a citizen of the United States, and a resident of Pittsburg, in the county of Walker, 5 and State of Georgia, have invented a new and Improved Leveling-Rod, of which the following is a full, clear, and exact description.

My invention relates to leveling-rods, and more particularly to those which are extensible. Its principal objects are to provide such a device which may be read directly by the observer at all extensions.

It consists in the various features and combinations hereinafter described and more particularly claimed.

Reference is to be had to the accompanying drawings, forming a part of this specification, in which similar characters of reference indicate corresponding parts in all the figures.

20 Figure 1 is a broken front elevation of one embodiment of my invention. Fig. 2 is a similar side elevation thereof. Fig. 3 is a transverse sectional detail through the tape-reel. Fig. 4 is an enlarged perspective view 25 of the head of the rod, and Fig. 5 is a horizontal section on the line 5 5 of Fig. 2.

10 designates the lower section of the rod, this being protected at its bottom extremity by a shoe 11. At its upper end is fixed a guide 30 13, through which moves an upper rod-section 14, carrying at its lower end a guide 15, surrounding the lower section. Threaded through a sleeve or boss 16 at one side of the guide 13 is a clamping-screw 16^a, which may serve to 35 force a clamping member 16^b against the side of the upper section.

Fixed to the face of the section 10 conveniently in a shallow groove therein is a flexible scale, here shown as consisting of a tape 17 of 40 some suitable material, as thin metal or fabric. At the upper end of the rod-section 14 is a head or enlargement 18, to which is fixed a casing which, as illustrated, consists of side pieces 19 19 and a cap 20 secured thereto.

45 The head has at each side a groove 21, continuing a recess 22 between the sections, and the sides of the casing are divided to clear this groove. The purpose of the channel thus formed will be hereinafter stated. Extending between the sides of the casing is a spindle 23, upon which rotates a reel consisting

of a drum 24 and cheeks 25. This reel is held normally in one direction by a spring 26, fastened at one end to the spindle and at the opposite end to the drum. The tape 17 is wound 55 about this drum and secured thereto at its inner end. Immediately below the reel, with its outer face preferably located substantially in the plane of the graduated face of the lower section, is a guide member, here shown as a 60 roll 27, journaled at its ends in the sides of the casing. Below this guide-roll the head is provided with a grooved face 28, similar to that in which the tape is fixed upon the lower section.

65 In the ordinary type of extension-rod the scale-graduations are so applied to them that it is impossible to read these consecutively from the lower to the upper section except when the rod is extended to its full height. In 70 situations where there is limited head room—such as in mines, sewers, and buildings—it is often impossible to secure this complete extension, and in such cases a target must be resorted to. This requires considerable time 75 for accurate setting, and unless operated by a skilled rodman who can read the verniers the rod must be carried back to the observer for each reading. With my improved rod this is unnecessary, for as the upper section 80 is raised upon the lower the tape, which is continuously graduated from its lower end, is drawn off the reel over the guide-roll 27 and adjacent face 28, and thus furnishes consecutive graduations, this continuing from a 85 position of minimum to full extension, enabling the observer to read the levels directly through his instrument. If, however, it is desirable to obtain more accurate readings, the rod may be provided with the usual target 90 T, carrying verniers, which is indicated in dotted lines in Figs. 1 and 2 of the drawings; this target having its guide members operating in the channel formed by the groove 21 and recess 22.

95 Having thus described my invention, I claim as new and desire to secure by Letters Patent—

1. A leveling-rod comprising sections movable relatively to one another, and a flexible scale member fixed to one of the sections and 100 movable over the other.

2. A leveling-rod comprising sections mov-

- able relatively to one another, a flexible scale member fixed to one of the sections, and a reel upon another section with which the scale member coacts. 35
5. 3. A leveling-rod comprising sections movable relatively to one another, a flexible scale member fixed to one of the sections, a reel upon another section with which the scale member coacts, and means for rotating the reel. 40
10. 4. A leveling-rod comprising sections movable relatively to one another, a flexible scale member fixed to one of the sections, a reel upon another section with which the scale member coacts, and automatic means for rotating the 15 reel. 45
15. 5. A leveling-rod comprising two sections sliding upon one another, a tape secured to one section, and a reel carried by the other section and upon which the tape is wound. 50
20. 6. A leveling-rod comprising two sections sliding upon one another, a tape secured to one section, a reel carried by the other section, and a clamp connecting the sections. 55
25. 7. A leveling-rod comprising two sections sliding upon one another, a tape secured to one section, a reel carried by the other section and upon which the tape is wound, and a spring acting upon the reel. 60
30. 8. A leveling-rod comprising two sections sliding upon one another, a tape secured to the face of one section and movable upon the other, and a support for the tape carried by the latter section. 65
35. 9. A leveling-rod comprising two sections
- sliding upon one another, a tape secured to the face of one section and movable upon the other, a support for the tape carried by the latter section, and a guide carried by the last-named section and lying substantially in the plane of the face of the first section. 70
10. The combination with a rod having two sections, of a head carried by one section, a reel mounted within the head, and a tape extending over the reel to the other section. 75
11. The combination with a rod having two sections, of a head carried by one section, a reel mounted within the head, and a tape extending over the reel and fixed to the other section. 80
12. The combination with a rod having two sections, of a head carried by one section, a spindle fixed in the head, a reel rotatable about the spindle, and a tape extending over the reel and fixed to the other section. 85
13. The combination with a rod having two sections, of a head carried by one section, a spindle fixed in the head, a reel rotatable about the spindle, a spring attached to the spindle and reel, and a tape extending over the reel and fixed to the other section. 90

In testimony whereof I have signed my name to this specification in the presence of two subscribing witnesses.

WILLIAM BRYAN SHROPSHIRE.
